UNITED STATES PATENT OFFICE.

JOHN BRAINERD MORGAN AND MORRIS F. CLARK, OF ROCHESTER, NEW YORK, ASSIGNEES TO MORGAN-CLARK SYSTEM COMPANY, OF DETROIT, MICHIGAN, A CORPORATION OF MICHIGAN.

RADIATOR-VALVE.

985,196.

Specification of Letters Patent.

Patented Feb. 28, 1911.

Application filed June 13, 1910. Serial No. 566,477.

To all whom it may concern:

Be it known that we, JOHN BRAINERD MORGAN and MORRIS F. CLARK, of Rochester, in the county of Monroe and State of New York, have invented certain new and useful Improvements in Radiator-Valves; and we do hereby declare the following to be a full, clear, and exact description of the same, reference being had to the accompanying drawings, forming a part of the specification, and to the reference-numerals marked thereon.

Our present invention relates to valves and particularly to that class adapted to be used in connection with the radiators of heating systems, and it has for its object to provide a radiator valve which is adapted for use in conjunction with vapor or low pressure steam heating systems in which a circulation is maintained in the various pipes and radiators by a pump or other means employed for creating a partial vacuum for the purpose of drawing off the water of condensation.

Our invention also has for its further object to provide a valve of this character consisting of few parts of simple construction so arranged that they may be readily assembled and adjusted and which in operation will normally clear their valve seats and vents from scale or other foreign substances.

To these and other ends the invention consists in certain improvements and combinations of parts all as will be hereinafter more fully described, the novel features being pointed out in the claims at the end of the specification.

In the drawings: Figure 1 is a vertical sectional view showing the preferred construction of a valve embodying the invention. Fig. 2 is a horizontal sectional view taken on the line 2^x—2^x of Fig. 1. Fig. 3 is a vertical sectional view showing a modified form of valve. Fig. 4 is a view showing in side elevation a portion of a radiator illustrating the valve attached thereto, and Fig. 5 is an enlarged detail sectional view taken on the line 5^x—5^x of Fig. 1.

Similar reference numerals in the several figures indicate similar parts.

In the so-called vacuum heating systems in which the radiators are connected to the supply and return pipes a proper circulation is maintained by drawing off the air and water of condensation by means of a vacuum pump, and it is, therefore, desirable to locate

at some point in the return pipe, and preferably in proximity to the radiator a check valve.

The object of our present invention is to provide such a valve which may be conveniently adjusted so that it may be operated by the suction or vacuum created in the return pipe when the water of condensation in the radiator shall have reached a predetermined point. In a valve of this character it is also desirable that a vent be provided whereby the air accumulated in the radiator, when the latter is not in use, may be gradually drawn off, or through which a very small quantity of the vapor may pass, in order that when the inlet valve of the radiator is first opened the radiator may be quickly heated by the steam or vapor admitted thereto. It is also essential that provision be made to keep the vent from becoming clogged or rendered ineffective by the deposit of scale thereon or the lodgment of foreign substances therein and that the valve seat be also kept clear and free of such material.

A valve constructed in accordance with our invention comprises the casing or body 1 having the inlet passage 2 which is connected with the radiator 3 by a short length of pipe 4. The outlet passage of the valve indicated by 5 is arranged at right angles to the inlet passage and is connected with the return pipe 6. Between the inlet passage and outlet passage and preferably arranged at the inner end of the latter is a wall or partition 7, having on its lower side the valve seat 8, with which co-operates the valve head 9. The latter is arranged to move in the direction of the outlet passage, to open the valve, but is normally retained yieldingly in engagement with its seat by the spring 10 operating on the valve stem 11. The stem extends upwardly from the valve head through the wall 12 which is screw-threaded in the collar 13 of the casing opposite to the outlet passage and located above the inlet passage, said wall being provided with a perforation through which the valve stem passes and having a central hub 14 provided with a transverse slot 15 in which a screw driver or other suitable tool may be fitted when it is desired to remove or apply the wall 12. The hub 14 also provides a means for centering the lower end of the spring 10, the upper end of which

bears against an adjustable head or cap 16 threaded on the stem 11, which may be moved longitudinally thereon to vary the compression of the spring and thus regulate the pressure with which the valve head 9 is held against its seat 8.

The valve stem is provided with a longitudinal perforation 17, and at one side of the stem is a laterally extending slot 18, forming the vent or port which opens communication between the inlet and outlet passages of the valve casing, the area of which is controlled by the closeness with which the cleaning member 19 is fitted between the walls of the slot, or the relationship which its lower end may bear to the corresponding end of said slot when the valve head is in engagement with its seat. The cleaning member 19 is bent laterally at its upper end forming the extremity 20 overlying the outer face of the wall 12, where it is provided with an eye 21 receiving the screw 22 which rigidly secures it in position on the wall. The end 20 of the cleaning member passes through the slot 15, at one side of the boss 14, and its downwardly projecting end lying in the slot in the valve stem also serves to prevent the latter from rotating when the cap 16 is adjusted. The limit of the downward movement of the valve head is determined by the position of the upper end of the slot 18 in reference to the end portion 20 of the cleaning member, and the aperture thus formed, which under some circumstances would permit the escape of vapor, is closed by the pin 23 inserted in the upper end of the member 17, its head 24 engaging the upper end of the valve stem beneath the cap 16. This pin may be easily removed whenever it is desired to insert an instrument should it become necessary to remove any obstruction which might become lodged in the passage in the stem.

45 The parts of the valve mechanism arranged exteriorly of the casing are preferably inclosed by the dome-shaped cap 25 engaging the screw threads in the collar 13.

In operation, when the suction in the outlet passage 5 and the weight of the water of condensation bearing upon the upper side of the valve head becomes sufficient to overcome the tension of the spring 10, the valve head 9 will be moved downwardly 55 away from its seat, allowing the water in the radiator to flow outwardly and as the valve head opens in the direction of the outlet passage any sediment that may have been deposited in the valve casing will be flushed 60 out, at the same time the normal area of the vent will have been increased and the stream of water flowing through the slot 18 and the perforation 17, will wash away any foreign substance therein. At the same 65 time the reciprocation of the valve stem rel-

atively to the cleaning member 19 will cause the latter to dislodge any particles of scale which may have found lodgment in or against the slot 18. The latter, it will be noticed from Fig. 5, is also less in width 70 than the diameter of the perforation 17, so that any minute particles of foreign matter which may be carried through the lower end of the slot, when the valve head is opened, will find ready outlet through said perforation. The pin or finger forming the cleaning member 19 being stationary and projecting into the laterally extending portion of the vent or port coöperates with the lower end thereof so that the size of the port is 75 automatically increased when the valve head moves away from its seat and reversely the area of the port is automatically diminished during the return of the valve head under the influence of the spring 10. When the 80 valve is closed the vent or port primarily acts to allow the escape of air or vapor and as the level of the water seal in the valve chamber increases a portion of the water may drip through the port, but when the 85 valve head is opened the stem is drawn downwardly and the port entirely submerged when it becomes an auxiliary exit to the main passage through the valve seat and some of the water, air and vapor escaping through it thoroughly flushes away any foreign particles or sediment. The 90 cleaning member also acts during the operation of the valve head to remove any deposits of scale or corrosion which may have 95 a tendency to become deposited on the walls of the port and which in time would become a menace to its successful operation.

In the modified form of the valve shown in Fig. 3, a somewhat different arrangement of the cleaning member is illustrated. In this valve the tubular stem 30 is provided with an aperture 31 extending through the stem at an angle and intersecting the perforation in the stem, its lower 100 end forming the vent and affording communication between the body of the casing and the interior of the stem below the partition 32. The cleaning member, indicated by 33, has the free end projecting through the vent 31 and intermediate its length it is provided with a coil 34 giving it the desired amount of elasticity to permit it to accomodate itself to the longitudinal movement of the stem and to effect the reciprocal movement of the cleaning member in the vent during the movement of the stem. The cleaning member is held in position by securing its outer extremity beneath the head of the screw 35. When the cleaning member is thus constructed, the valve stem is prevented from rotary movement by providing it with a pin 36 fitting a slot in a finger 37 projecting upwardly 115 from the partition 32.

A valve constructed in accordance with our invention possesses the advantage of maintaining a water seal for preventing the leakage of steam or vapor around the valve seat and thus permitting the quantity of vapor allowed to escape through the vent to be determined to a nicety, hence the spring 5 may be regulated to render the valve head sensitive in operation, so that it will 10 automatically release each time the water of condensation reaches a predetermined height.

The arrangement of the parts as described, whereby the valve head opens outwardly in the direction of the return pipe 15 of the heating system and at the same time opens and increases the area of the vent, not only permits these parts to be cleaned by the outflowing water of condensation, 20 but also permits the same result to be accomplished by temporarily increasing the steam pressure in the supply pipe and radiator, an expedient which may be employed should occasion arise.

25 We claim as our invention:

1. The combination with a valve casing having a valve seat and a movable valve head coöperating therewith having a stem provided with an automatic opening port, 30 of a cleaning member arranged stationary in conjunction with said port and coöperating with the port to increase the size of the opening of the said port upon the movement of the valve head in a direction away 35 from its seat.

2. The combination with a casing forming a valve chamber having inlet and outlet passages, a valve seat located between them and a valve head coöperating therewith having 40 a stem projecting exteriorly of the casing, the portion of the stem within the casing being provided with a vent opening communication between said passages, of a wall on the casing having a perforation through 45 which said stem passes, a spring bearing against the wall and operating on the stem to yieldingly hold the valve against its seat and a member also supported on said wall exteriorly of the valve chamber and projecting 50 into the vent for the purpose of cleaning foreign matter out of the latter upon each movement of the valve head.

3. The combination with a valve casing having inlet and outlet passages and a top 55 wall located opposite the outlet passage, a valve seat arranged between said passages, a valve head coöperating with said outlet passage having a stem projecting through the wall of the casing, said stem being provided with a vent, of an adjustable cap on 60 the stem, a spring arranged between it and the wall of the casing and a cleaning out member secured to the exterior of said wall and operating in the vent.

65 4. The combination with a valve casing

having inlet and outlet passages and provided with a collar arranged in alinement with the outlet passage, a perforated plate fitted in said collar, a valve seat and a valve head coöperating with the seat and movable 70 relatively thereto in the direction of the outlet passage, of a valve stem extending through the plate provided with a longitudinal perforation and a laterally extending vent leading therefrom, an adjustable head 75 on the stem and a spring arranged between it and the plate and a cleaning member secured to the latter and having its extremity projecting downwardly and lying in the vent.

5. The combination with a valve casing having inlet and outlet passages and provided with a collar arranged in alinement with the outlet passage, a plate threaded in said collar having a perforated central hub 80 provided with a slot, a valve seat and a valve head coöperating with the seat and movable relatively thereto in the direction of the outlet passage, of a valve stem extending through the plate provided with a longitudinal perforation and a laterally extending vent leading therefrom, an adjustable head on the stem, a spring arranged between it and the plate and a cleaning member secured to the latter and having its extremity projecting through the slot in the hub 85 and lying in the vent opening of the stem.

6. The combination with a valve casing having inlet and outlet passages and provided with a collar arranged in alinement with the outlet passage, a plate threaded in said collar having a perforation, a valve seat and a valve head coöperating with the seat and movable relatively thereto in the direction of the outlet passage, of a valve stem extending through the plate provided with a longitudinal perforation and a laterally extending slot leading from a point below to a point above the plate, a cleaning member lying in the slot having its outer extremity projecting laterally over the face of the plate, a pin removably fitted in the upper end of the stem and closing the end of the slot above the cleaning member and means for yieldingly holding the valve head 110 in engagement with its seat.

7. The combination with a valve casing having inlet and outlet passages, the former being located above the latter, a valve seat and a valve head coöperating therewith to form a water seal and movable in the direction of the outlet passage, of a stem attached to the valve head and projecting exteriorly of the casing, said stem being provided with an auxiliary air and water passage opening direct communication between said inlet and outlet passages, means co-operating with said auxiliary passage for automatically enlarging and diminishing its 120 125 130

- area upon the movement of the valve head and means operating to support the valve head and cause it to form with the water of condensation an unbroken water seal.
8. The combination with a valve casing forming a chamber having inlet and outlet passages, said chamber constituting one element, the inlet passage being located above the outlet passage and the latter having a valve seat, of a valve head coöperating with the latter to cause water of condensation to form a continuous water seal, a stem attached to the valve head and projecting exteriorly of the casing, said stem and head constituting a second element, one of said elements being provided with an auxiliary air and water passage opening communication between the inlet and outlet passages at a point within the water seal chamber, means operating on said stem exteriorly of the casing to counteract a fixed quantity of water forming the seal and means coöperating with the auxiliary passage for cleaning it automatically upon each operation of the valve.
9. The combination with a valve casing having a valve seat and a movable valve head coöperating therewith having a stem

provided with an automatic opening port leading from one side of the valve seat to the other, of a cleaning member supported on the casing and projecting into the port, said port and member coöperating to increase the area of the opening of the port when the valve is moved into open position in a direction away from its seat.

10. The combination with a valve casing having a valve seat, and a movable valve head coöperating therewith having a stem provided with a port comprising a longitudinally extending passage having an extremity opening laterally of the valve stem and a cleaning member lying in the lateral portion of said passage.
